CLAIM

The ornamental design for an unmanned aerial vehicle, as shown and described.

DESCRIPTION

FIG. 1 is a front isometric view of an unmanned aerial vehicle showing the claimed design.

FIG. 2 is a rear isometric view thereof.

FIG. 3 is a top plan view thereof.

FIG. 4 is a bottom plan view thereof.

FIG. 5 is a front elevation view thereof.

FIG. 6 is a rear elevation view thereof.

FIG. 7 is a right side elevation view thereof; and,

FIG. 8 is a left side elevation view thereof.

The broken lines in the drawings depict portions of the unmanned aerial vehicle that form no part of the claimed design. The unshaded portions of the unmanned aerial vehicle between solid and broken lines form no part of the claimed design.

1 Claim, 8 Drawing Sheets
